FLYER

Philip A. Gwaltney, McColl, S. C., and William G. Reynolds, Charlotte, N. C.

Application October 29, 1935, Serial No. 47,246

3 Claims. (Cl. 118—57)

This invention relates to improvements in flyers for roving frames and relates especially to means for compacting the roving as it passes through the presser foot so that the short fibers 5 will be rendered parallel to each other as well as parallel to the longer fibers.

In the process of drawing the slivers in roving frames the purpose is to gradually reduce the sliver or roving in size and at the same time render all of the fibers parallel to each other to increase their strength when they are twisted or spun. In drawing frames, the long fibers are engaged by the rolls and are straightened out due to the front rollers travelling much faster than the middle rollers, and the middle rollers rotating at a greater number of revolutions per minute than the back rollers. This causes a proper placing of the longer fibers, but the short staple occurring along with the long staple is not rendered parallel as the rollers do not get the proper bite thereon. By passing the sliver through a constricted eye on the presser foot this condenses the fibers and causes a parallelization of the short staple also. By having the small hole and condensing the sliver as it passes therethrough, air currents are prohibited from passing through this hole. Heretofore, there has been a large hole and no condensing of the sliver, thus resulting in a stream of air being forced through this hole to disrupt the fibers, and especially the short fibers.

This improved presser foot is designed for use on any type of flyer frame and when used on twisters the improved presser foot, especially in a wet twist operation, will cause the projecting short fibers to be pressed flat and while in such condition will be laid onto the yarn package.

Some of the objects of the invention having been stated, other objects will appear as the description proceeds, when taken in connection with the accompanying drawing, in which:—

Figure 1 is a transverse vertical sectional view taken along through a portion of a roving frame showing the invention applied thereto;

Figure 2 is a vertical sectional view through the central portion of the flyer mechanism shown in Figure 1;

Figure 3 is a sectional plan view taken along the line 3—3 in Figure 1;

Figure 4 is a sectional view taken along the line 4—4 in Figure 1;

Figure 5 is a sectional view taken along the line 5—5 in Figure 1;

Figure 6 is an enlarged detail view of the free end of the roving strand guiding mechanism;

Figure 7 is an isometric view of the roving strand guide mechanism detached from the flyer.

Referring more specifically to the drawing, the numeral 10 denotes a portion of a roving frame which has mounted on the upper portion thereof a plurality of roll stands 11, only one of which is shown, having lower rolls 12 and upper rolls 13 rotatably mounted therein. Between these rolls is adapted to pass a strand of roving which roving is constantly reduced in size as it progresses from the carding machine through various drawing operations. From the rolls 12 and 13 the roving passes through the hole 15 in the upper portion of flyer 16 and then outwardly through hole 17, around the top portion of the flyer and again downwardly through the interior of leg 18 of the flyer 16. Another leg 19 is disposed on the opposite side of the pivot point of flyer 16 in order to counter-balance the flyer about its point of rotation. The flyer 16 has a pin 20 penetrating the upper end thereof which is adapted to fit in slot 21 in the upper end of spindle 22. It will be noted that the upper end of spindle 22 is slightly tapered and is adapted to fit into cavity 23 in flyer 16.

The lower end of spindle 22 has a beveled gear 25 fixedly secured on the lower end thereof which gear is adapted to mesh with a larger bevel gear 26 fixedly secured on longitudinally disposed shaft 27. When shaft 27 is rotated, it is evident that rotation will be imparted to shaft 22 and to the flyer 16. The intermediate portion of shaft 22 is rotatably mounted in bracket 28 and tubular member 29 which is integral with bracket 28, said bracket being secured to traverse rail 30 by any suitable means such as bolts 31.

Rotatably mounted on tubular member 29 is a bevel gear 35 which gear meshes with a larger gear 36 mounted on longitudinally disposed shaft 37. The upper end of the hub portion of gear 35 has a rim 39 integral therewith upon which is adapted to rest the base of a bobbin or quill 40. It will be noted that the rim 39 has an upwardly projecting member 42 integral therewith which is adapted to fit into a slot in the lower end of quill 40 in order to cause the quill to rotate along with the gear 35. In the operation of the machine both the flyer 16 and the quill 40 rotate in the same direction but the bobbin 40 rotates at a higher rate of speed than the flyer 16 in order that the yarn may be wound onto the bobbin.

Loosely mounted around the upper central portion of leg 18 is the upper portion of presser 44. Presser 44 has a circular portion 45 on the upper end thereof which surrounds the leg 18 and the

lower portion of presser 44 also has a circular portion 46 surrounding the lower portion of leg 18. Integral with the lower end of presser 44 is presser foot 47 which has a plate 47a on the free end thereof, said plate having a centrally disposed hole 48 cut therein through which the roving strand 14 passes. After the strand 14 leaves the lower end of leg 18 it is wrapped twice around the presser foot 47 and is then placed in hole 48 through the slot or passageway 50 cut in the upper surface of plate 47a. The plate 47a has a slight groove 51 cut on the interior surface of the plate adjacent the package of yarn in order to guide the strand in a measure after it leaves the eyelet or hole 48.

By observing Figures 4 and 6, it is seen that the hole 48 is larger at the point of entrance of the yarn than it is at the point of exit of the yarn, and also set at an acute angle to the sides of plate 47a. Since the yarn, which passes through this hole, is sufficiently large to fill the entire hole, this converging and condensing feature has a tendency to cause the fibers in the strand of roving or yarn to be compacted and also to be straightened out in parallel relation to each other. Were it not for the fact that this hole is constructed in this manner and of such a predetermined size as will fit the size of the strand of yarn drawn therethrough, there would be no converging feature, neither would there be a tendency to compact the strands and hold them in parallel relation to each other. Instead, there is a tendency when a large eyelet is used, that is, where the eyelet is very much larger than the strand drawn therethrough, for the fibers to fuzz up. Due to the rapidity at which the strand passes through the hole in con-

ventional presser foots, the currents of air will cause the fibers to flow outwardly on the outside of the strand as the air is drawn through the large hole 48 and therefore defeat the principal object of the drawing out process which is to cause the fibers to be straightened out in parallel relation to each other. By having a funnel-shaped hole which is filled by the strand passing therethrough the air is not permitted to enter the hole in the presser foot and therefore the disrupting factor of the air passing through said hole is eliminated.

In the drawing and specification there has been set forth a preferred embodiment of the invention and although specific terms are employed, they are used in a generic and descriptive sense only, and not for purposes of limitation, the scope of the invention being set forth in the appended claims.

We claim:

1. An improved flyer for flyer frames comprising a presser foot having a funnel-shaped eye therein through which is passed a strand normally larger than the smallest portion of the eye.
2. A presser foot for flyers having a hole therethrough which is funnel-shaped and disposed at an acute angle to the plane occupied by the presser foot.
3. That method of spinning which comprises winding a strand onto a package and converging and condensing the strand as it is wound onto the package by passing it through a funnel-shaped passageway whose restricted portion is smaller than the normal thickness of the strand.

PHILIP A. GWALTNEY.
